UNITED STATES PATENT OFFICE.

FRANK v. ZIEKURSCH, OF MILWAUKEE, WISCONSIN.

FUSE PLUG.

Application filed February 12, 1920. Serial No. 358,082.

To all whom it may concern:

Be it known that I, FRANK v. ZIEKURSCH, a citizen of the United States, residing at Milwaukee, in the county of Milwaukee and State of Wisconsin, have invented new and useful Improvements in Fuse Plugs, of which the following is a specification.

This invention relates to a fuse plug.

An object of the invention is to provide an improved renewable fuse plug.

Another object is to provide for fuse plugs renewable fuse elements which may be easily and quickly positioned therein.

Another object is to provide improved means for holding a terminal of the fuse plug in position.

Another object is to provide an improved unitary renewable terminal and fuse for fuse plugs.

Another object is to provide an improved fuse plug wherein one of the terminals thereof is resiliently held in position.

Another object is to provide an improved fuse plug wherein positive contact is insured between the center terminal thereof and the cooperating terminal of the associated receptacle or socket.

Other objects and advantages will appear from the description and claims.

An embodiment of the invention is illustrated in the accompanying drawings wherein,

Figure 1 is a side elevation of the fuse plug;

Fig. 2 is a vertical section on line 2--2 of Fig. 1;

Fig. 3 is a bottom plan of the fuse plug;

Fig. 4 is a top plan of the fuse plug with the cap or cover thereof removed; and

Fig. 5 is a perspective of the unitary renewable terminal and fuse of the fuse plug.

The fuse plug comprises a hollow cylindrical plug 1 of suitable insulating material, such as, for example, porcelain, having the usual threaded terminal forming shell 2 surrounding the lower portion of the plug.

An exteriorly threaded flange 3 is formed at the upper end of the plug 1. A cap 4 having a central opening 5 has screw threaded engagement with the threaded flange 3.

A window 6 of suitable material, such as, for example, mica, is provided for the opening 5 and is maintained in position by means of the cap 4.

The plug 1 near its upper end is provided with a side opening 7 in which is

positioned an L-shaped bracket 8. The lower end of this bracket extends down between the plug 1 and the terminal forming shell 2, to which the bracket 8 may be 60 soldered or otherwise electrically connected. The laterally extending arm of the bracket 8 carries a screw 9 by means of which one end of the fuse may be connected thereto.

The base of the plug 1 is provided with 65 a rectangular opening 10 through which the fuse is inserted into the fuse plug and which cooperates with attaching means for securing the center or second terminal 11 to the fuse plug.

The center terminal 11 and the fuse 14 form the renewable element of the fuse plug. The center terminal 11 is formed from a strip of suitable material, such as, for example, brass, and attached thereto are two 75 resilient arms 12 and 13 between the free ends of which is secured the fuse 14.

The center terminal 11 and the attached arms 12 and 13 may be formed from sheet metal, the arms being integral with the terminal. These arms 12 and 13 which extend upwardly from the terminal 11 are oppositely bowed as clearly indicated in Figures 2 and 5. The upper or free ends of the arms are grooved to receive one end of the 85 fuse wire 14. The fuse wire and the upper ends of the arms 12 and 13 may be soldered or otherwise rigidly connected so that the fuse wire is both rigidly and permanently fastened to these arms. The fuse may, of 90 course, take the form of a strip or ribbon instead of a wire, if desired.

The laterally extending portions 12^a and 13^a of the arms 12 and 13 rest against the base of the plug when the combined terminal 95 and fuse is secured to the plug. These laterally extending portions 12^a and 13^a, which are resilient, are spaced a short distance from the terminal 11. Thus the resiliency of these portions 12^a and 13^a insures that positive contact is made between the terminal 11 and the cooperating terminal of the socket or receptacle into which the fuse plug is inserted. This positive contact is insured even though the depth of the 105 receptacles or sockets may vary slightly.

When placing the combined renewable terminal and fuse in position in the fuse plug, the fuse is inserted through the opening 10 and the arms 12 and 13 forced into 110 this opening. The over-all distance between the outer surfaces of the arms 12 and 13

is slightly greater than the width of the opening 10 so that these arms are compressed when forced into the opening. These arms, therefore, frictionally engage 5 the walls of the opening 10 and maintain the center terminal attached to the plug. The terminal 11 and the fuse are, therefore, definitely attached to and positioned in the fuse plug. The upper end of the 10 fuse is clamped to the terminal bracket 8 by means of the screw 9.

The flat terminal 11 may have stamped thereon any suitable mark or number to indicate the normal current carrying capacity 15 of the fuse attached to this terminal.

If the fuse is blown the remnants of the renewable element may be readily removed from the fuse plug. The terminal 11, together with the attached arms 12 and 13 and 20 such portion of the fuse as may remain connected therewith may be easily and quickly removed by merely inserting the end of a screw driver or the blade of a knife between the terminal 11 and the base of the fuse, and 25 thus forcing the arms 12 and 13 out of the opening 10. Then after removing the cap 4 the screw 9 may be loosened to remove from the bracket any portion of the old fuse which may remain connected therewith. A new 30 combined renewable terminal and fuse may then be inserted in the fuse plug and the upper end of the fuse wire fastened to the terminal bracket 8 as before described. After the cap 4 and the window 6 have been re- 35 placed the fuse plug is ready to be connected in circuit again.

The invention contained herein is of course susceptible of other embodiments and adaptations.

40 What is claimed is:

1. A fuse plug having in combination a hollow insulating plug having an opening in the base thereof, a threaded terminal forming shell surrounding the insulating plug, a second terminal, resilient arms attached thereto and abutting the base of the plug, resilient attaching means connected with the resilient arms and frictionally engaging the opening for attaching the terminal to the plug, and a fuse within the plug electrically connecting said terminals.

2. A fuse plug having in combination a hollow insulating plug of unitary structure and having an opening in the base thereof, 55 a threaded terminal forming shell surrounding the insulating plug, a resilient terminal, a pair of resilient arms connected with the resilient terminal and extending through the opening, and a fuse connected with the free ends of said arms electrically connecting said terminals.

3. A fuse plug having in combination a hollow insulating plug having an opening

in the base thereof, a threaded terminal forming shell surrounding the insulating 65 plug, a resilient terminal, a pair of resilient arms connected with the resilient terminal and so formed that the said terminal is attached to the plug by the frictional engagement of said arms with the walls of said 70 opening, and a fuse within the plug electrically connecting said terminals.

4. A unitary terminal and fuse for use with a fuse plug, comprising a terminal, a pair of resilient attaching arms, a pair of 75 upwardly extending resilient arms connected to said attaching arms and adapted to frictionally engage an opening in the fuse plug for attaching the terminal thereto, and a fuse secured to said terminal.

5. A unitary terminal and fuse for use with a fuse plug, comprising a terminal, upwardly extending and oppositely bowed resilient arms extending therefrom, and a fuse rigidly and permanently connected to the 85 free ends of said arms.

6. A unitary terminal and fuse for use with a fuse plug, comprising a terminal, a pair of arms attached thereto and bent over in a plane substantially parallel with the 90 terminal, a fuse, and resilient connecting means between the fuse and arms adapted to enter an opening in the fuse plug thereby to attach the terminal thereto.

7. A unitary terminal and fuse for use 95 with a fuse plug, comprising a terminal, upwardly extending and oppositely bowed resilient arms extending therefrom, the free ends of said arms being provided with complementary grooves, and a fuse positioned 100 in the grooves and rigidly and permanently connected to the free ends of said arms.

8. A terminal for use with a fuse plug having an opening in its end wall, comprising a disk, two resilient arms attached to opposite edges of the disk and overlying the disk and spaced therefrom, and upwardly extending extensions for the arms projecting through the opening in the plug, whereby the terminal is attached to the plug by 110 means of the resilient arms.

9. A unitary terminal and fuse for use with a fuse plug, comprising a disk terminal, a pair of resilient attaching arms integrally united to opposite edges of the terminal and overlying the same in spaced relation thereto, upwardly extending outwardly bowed resilient arms integrally united to the free ends of the attaching arms, and a fuse positioned between the free 115 ends of the upwardly extending arms and rigidly and permanently fastened thereto.

In witness whereof, I have hereunto subscribed my name.

FRANK v. ZIEKURSCH.
